COMBINATION BEVERAGE DISPLAY AND
REFRIGERATING UNIT

Morris Stern, Indiana, Pa.

Application May 6, 1949, Serial No. 91,822

1 Claim. (Cl. 62—89.5)

1
This invention relates to a beverage display and refrigeration unit and more particularly to a simple, self-contained device, which is readily adaptable to any location, requiring no installation work other than setting same in the desired location and then plugging the electrical connection into a convenient electrical outlet.

An object of my invention is the provision of an improved display unit which is practical in construction, easy to obtain access to and exceedingly light in relation to similar units now in use.

Another object of the invention is to provide means whereby each beverage container is placed in an individual receptacle, surrounded by a refrigerating coil supplied with a cooling medium from a centrally located condensing unit.

Further, an advantage of my improvement lies in the extreme simplicity of arrangement of the above-mentioned coils in relation to each other and to the condensing unit itself. By my arrangement all the beverage containers will receive an equal amount of refrigeration, and since the coils are in close contact therewith a positive amount of cooling will be supplied to each receptacle.

A still further object lies in the provision of a condensation collecting means or sluice-way to receive the droplets from each receptacle and its associated cooling means and to relay same to a central drip pan means.

Still other objects and advantages will become apparent from the following description of the present invention illustrated in the accompanying drawing, in which:

Figure 1 is a perspective view of my display and refrigerating unit.

Figure 2 is a side elevation taken with the side removed and showing the relation of the various parts of the device.

Figure 3 is an enlarged cross section taken on one of the receptacles and showing the particular wall structure of the device.

Similar reference characters represent similar parts in the several figures.

Refrigerated display counters in use at the present time take on several forms. In one type of structure the article to be refrigerated is set on a semi-enclosed shelf open to the outside air. Means are provided whereby a cool air circulating system lowers the temperature of the article. This type of unit is subject to constant loss of cool air to the outside surroundings, thereby necessitating a large cooling plant which makes the display case larger and heavier, and the cooling plant more expensive to operate.

2
Another form of refrigerated display case utilizes a plurality of large enclosed refrigerated containers, each container adapted to receive a plurality of articles of merchandise. With such an arrangement a great amount of the cooling medium is used up in cooling the space in the container not used for articles to be refrigerated.

As an improvement over refrigerating units heretofore presented I have devised a structure which is a portable self-contained unit easily installed, and readily accessible to repair, and which has a simple effective way of distributing the cooling medium to beverage container receptacles. Also provided is an efficient means for taking away condensation formed on the cooling medium distributing means.

In the drawings, the display case is generally designated by the numeral 10 and comprises a housing having a tiered, step-like front and top portion with risers 11 and horizontal members 12, respectively, side panels 13, and a back portion 14. A bottom 15 is provided upon which is mounted a refrigerating unit, generally designated as 16.

Also mounted on the bottom are rubber feet 17 to prevent marring of the surface upon which the unit is placed and to further prevent accidental movement of the display case. The back enclosing portion 14 is cut from hardware cloth which is of heavy wire mesh providing ample ventilation for the condensing unit 16. The other enclosing panels are of two-part construction, as best shown in Fig. 3, the outer part 27 being of a suitable plastic material and the inner part 28 being of galvanized sheet metal. Such a construction provides sufficient body to support considerable weight and at the same time increases the aesthetic quality of the unit. Any suitable form of chrome trim 29 may be used at the seam formed by the meeting of said enclosing portions to enhance the attractiveness of this commercial display case. The side panels 13 are provided with louvres 18 to afford cross ventilation for the condensing unit 16.

The horizontal shelf-like members 12 are provided with a series of cup-like receptacles 19 depending below the surface thereof, and in which the bottles to be cooled and displayed are positioned.

The condensing unit 16 may be of any suitable construction largely depending on the size and number of receptacles 19 to be used.

The tubing 20 which carries the refrigerating medium is preferably of a soft pliable three-eighths inch copper stock. For purposes of clarity

in illustrating the coiling of the tubing around the receptacles and its connection to the condensing unit, Fig. 2 shows the circulation for a unit with a single receptacle for each tier. It is to be understood, however, that for a unit having a plurality of receptacles in each tier, the tubing would be successively coiled around each receptacle in the same tier and thence to the other tiers. The section of tubing adjacent the lower receptacle coil nearest the condensing unit is provided with a V-shaped portion 21, the purpose of this construction being to prevent any condensate from being carried along the coil to the condensing unit.

Beneath the coils and receptacles there is provided a galvanized sheet metal condensation receiving means or sluice-way 22 which is adapted to carry the droplets of condensation from the receptacles and coils to a drip pan 23 located in a forward lower portion of the case. The drip pan 23 is of the sliding drawer type and has a hand knob 26 on the outside thereof to facilitate removal from the case.

An aperture 24 is formed in the lower end of the sluice-way 22 to allow condensation to flow therefrom and also to allow the tubing to extend therethrough on its return to the condensing unit. The U-shaped portion 21 is formed immediately below the aperture 24 so that it will form a dropping point for condensation on the tubing. As previously set forth, this prevents the droplets from rising to the end portion 25 of the tube 20 which returns the cooling medium to the condensing unit 16.

As best seen in Figures 2 and 3 the space surrounding the receptacles and their coils contains an insulation medium 30 of spun glass. As will be apparent this insulation around the coils and receptacles gives almost one-hundred percent of the refrigerating capacity of the unit to the cooling of beverages and very little is lost in the transmission of the cooling medium from receptacle to receptacle. The particular composition of the insulation allows water droplets condensing on the coils and receptacles to drain therethrough to the drip pan 23.

Each receptacle 19 is provided with a centered aperture 31 in the bottom thereof and a short pipe 32 depending therefrom to allow the condensation to drain from the receptacle. Also provided is an apertured rubber disc 33 to be cemented in the bottom of said unit to prevent beverage containers from being broken when placed thereon.

From the foregoing description of my present invention it will be seen that the structural fea-

tures thereof aptly renders the device capable of handling large loads with a fraction of the refrigerating capacity of display units now in use.

Furthermore, because of the simple and efficient construction of my device it is very inexpensive to operate. For example, in the 12 receptacle case shown in Fig. 1, only a one-sixth horsepower condensing unit need be used, said unit being of the single cylinder hermetically sealed type. With such a unit the temperature of a beverage placed in the receptacle can be lowered from room temperature to 36° F. within twenty minutes. From this it can be seen that I have produced a device which is a decided improvement over commercial display cases heretofore devised, which required more time and larger condensing units.

While a preferred form of the invention has been shown and described, it will be understood that variation in details of form may be made without departure from the invention as defined in the appended claim.

I claim:

25 A cooling and display stand comprising a tiered structure having a plurality of vertically spaced surface levels, said surface levels having a plurality of openings formed therein, sleeve-like means located beneath each of said openings for supporting bottles therein, said means containing apertures in the lower end thereof, a coil surrounding each of the bottle supporting means and connected in series, a condensing unit positioned within the case and connected to each of said coils, an inclined sluice-way located beneath said bottle supporting means to receive condensate therefrom and to deliver same to a receiving pan, positioned at the lower end thereof, and insulating material in the space between the plurality of surface levels and the sluice-way, said material being closely packed around said coils and sleeve-like bottle supporting means.
